UNITED STATES PATENT OFFICE.

HERMAN LEINEWEBER, OF SOUTH CHICAGO, ILLINOIS, ASSIGNOR OF ONE-HALF TO
WILLIAM M. BAYNE, OF CHICAGO, ILLINOIS.

PNEUMATIC TOOL.

No. 866,370.

Specification of Letters Patent.

Patented Sept. 17, 1907.

Application filed February 27, 1907. Serial No. 369,566.

To all whom it may concern:

Be it known that I, HERMAN LEINEWEBER, a citizen of the United States, residing at South Chicago, in the county of Cook and State of Illinois, have invented a new and useful Improvement in Pneumatic Tools, of which the following is a specification.

The object of my invention is to enable the piston-stroke in a pneumatic-tool to be readily varied by the operator to diminish it, according to requirements of 10 the work being performed by the tool, below the full extent of the stroke for which the tool is constructed.

One form, and so far as I am now aware, the best form of means which I have devised for the aforesaid purpose is illustrated in the accompanying drawing, in 15 which—

Figure 1 is a vertical longitudinal section of a pneumatic tool provided with my improvement; Fig. 2, a view showing in perspective a broken portion of the trigger controlling the supply of air-pressure to the tool 20 for actuating the piston, with a stop adjustably supported upon it for regulating the extent of depression of the trigger to effect my piston-stroke-regulating purpose; Fig. 3, a view in elevation of the duct-containing bushing for the throttle-valve; Figs. 4, 5, 6, 7 and 8 are 25 sections taken, respectively, at the lines 4, 5, 6, 7 and 8 on Fig. 3 and viewed in the direction of the arrow; Fig. 9 is a view of the bushing in longitudinal section, showing the throttle-valve in elevation within it in the position wherein it produces one-third of the full or 30 normal piston-stroke; Fig. 10, a similar view of the same showing the throttle-valve in the position wherein it produces two-thirds of the normal piston-stroke, and Fig. 11, a similar view showing the position of the throttle-valve wherein it produces the full piston-stroke.

35 For illustrating my invention, I have selected the throttle-valve construction shown and described in Letters Patent of the United States No. 837,856, granted to me December 4, 1906, and the barrel and solid-piston construction forming the subject of my application, 40 Serial Number 342,179, filed November 6, 1906; so that reference to these may be had for a detailed disclosure of the tool herein illustrated in lesser detail, except as to the particular form of embodiment selected for illustrating my present improvement.

45 The barrel 12, into the forward end of which the stem of a tool-proper 13 is loosely inserted, contains a forward and relatively smaller air-chamber 14, shown to be divided by a central annular flange 15, and a larger rear air-chamber 16, on the base of which is a central boss 17 for cushioning the backstroke of the piston 18 and containing a central pressure-inlet port 19. The barrel-wall contains a plurality of longitudinal air-pas-

sages, preferably at uniform distances apart, one of which is indicated by dotted lines at 20 in Fig. 1. These passages lead from the forward chamber 14 rearwardly, and each terminates in a port indicated at 21. The barrel-wall also contains, to alternate with the passages 20, similar passages 22, one of which is indicated by dotted representation in Fig. 1, leading into the chamber 16 from a port indicated at 23. The piston shown is a solid body of uniform diameter throughout between its ends, except for circumferential grooves 24 and 25 provided about it respectively near its opposite ends. The actuating pressure for the full-stroke operation of the piston is supplied, as hereinafter described, 60 entering the barrel at a port 26 through a passage 27, whence it enters a branch-passage 28 through a port 29, the passage 28 having a rear port 30 and a forward port 31.

With the piston in the position represented, namely 70 at the end of its forward stroke, pressure will pass through the port 30 into the groove 25, whence it attains the chamber 14 through the ports 21 and passages 20 and drives the piston backward, escaping through exhaust-ports, one of which is shown at 32. In the retracted position of the piston its groove 24 registers with the port 31 to admit pressure through the ports 23 and 75 passages 22 into the rear chamber 16 for driving the piston forward, the pressure escaping through exhaust-ports 33. This is all in accordance with the operation 80 set forth in my aforesaid application.

A housing 34 is formed to extend diametrically across the wall of the rear end of the barrel forming the base of the handle 35, and terminates at one end in a restricted extension 36 into which is screwed the nipple 85 36' to connect the implement with the supply of air-pressure by a flexible tube (not shown). A tubular bushing 37, confined as a lining on the housing and open at the end nearest the port 26, where it contains a port 26' registering therewith, is closed at its opposite 90 end except for two grooves 38 and 39 formed longitudinally in its opposite sides to produce with the surrounding housing-wall air-ducts communicating at one end with the nipple and terminating at their opposite ends in ports 40 leading to the interior of the bushing; and 95 similar ports 41 lead from these ducts into the bushing beyond the center of the boss 17 coincident with the opening 19 in which is an opening 19' in the bushing-wall. A solid cylindrical throttle-valve 42, having a head 43 and recesses 45 and 45', is reciprocably confined and spring-pressed in the bushing to be actuated by a trigger 44 pivotally supported on the barrel to engage with the valve-head.

100 By the valved construction last described, when the

trigger is depressed against the resistance of the valve-spring to register the valve-recess 43 with the ports 40, thus establishing communication of the bushing-ducts with the port 26¹, the air-pressure is admitted into the 5 passage 27 for driving the piston in the manner described. If, at the start the piston should occupy a central dead-point position between the chambers 14 and 16, owing to balancing air-pressure in them, inasmuch as the valve-recess 45¹ is first brought, by the inward 10 movement of the throttle-valve, into registration with the port 19¹, air-pressure from that recess will enter the chamber 16 through the port 19 to act against the piston and drive it forward by overcoming the pressure at its impact-end in the chamber 14.

15 The described operation of the throttle-valve is the same as that set forth in my aforesaid Patent No. 837,856.

On the trigger, in a hole provided immediately underneath its thumb-piece, is confined a spring-pressed 20 rod 46, having a head 47 on one end and formed into a hook 48 at its opposite end. In the normal position of this rod its hook-end embraces the rear edge of the trigger just below the thumb-piece, as in Fig. 1, being held there by the retractive force of the spring. To 25 release the rod for adjustment, it is pressed at the head 47 against the resistance of the spring to free the hook, and permit the rod to be turned on its axis to register the end of the hook with one of a series (as two) of holes 49, 50, provided transversely through the web of 30 the trigger; and upon release of the rod, the spring will retract the end of the hook into the hole with which it then registers. In either of the two adjusted positions of the rod, its hook-end affords a stop by extending across the plane of the handle 35 which it encounters 35 in depressing the trigger, the hole 49, when the stop is in it, permitting the trigger to be depressed farther and the hole 50, when the stop is in it, permitting the trigger to be depressed less far; and when the stop is in its normal position, shown in Fig. 1, wherein it will not 40 encounter the handle, the trigger may be depressed to the full extent to produce the described full-stroke operation of the piston. But with the stop engaging either hole 49 or 50, the effect is to shorten the back-stroke of the piston and cause the latter to be driven 45 forward entirely by the pressure introduced against it through the port 19, because of the following-described ensuring conditions:

Fig. 9 shows the throttle-valve in the position relative to the ports 40 and 41 of causing the piston to make only one-third of the extent of its full back-stroke; Fig. 10 shows the same for producing only two-thirds of such backstroke, and Fig. 11 shows the relative position of the throttle-valve to cause the full backstroke of the piston. This division of the back-stroke into thirds is arbitrary and is stated by way of example, for the ports may be arranged, without departure from the invention, to vary the stroke to different proportions. As the parts are represented, when the stop 46 is adjusted into the hole 50, the resultantly 55 permissible extent of inward movement of the throttle-valve opens one-third of each port 40 to the ports 26¹, 26, permitting comparatively little pressure to pass through the passages 27, 28, port 30 and passages 20 into the chamber 14 to drive the piston back; and in making its 60 backstroke it will, when the piston covers the exhaust-

ports 33, encounter pressure in the chamber 16 introduced into it through the ports 19, 19¹, from the valve-recess 45¹ with which then, by the described inward movement of the throttle-valve, two-thirds of each port 41 register, thereby permitting relatively greater 70 pressure to enter the chamber 16. The air-pressure resistance in the chamber 16 is sufficient to prevent greater extent of backstroke of the piston than will permit its groove 24 to register with the exhaust-ports 75 32 and exhaust the pressure from the chamber 14; but this extent of backstroke is insufficient to register that piston-groove with the port 31, so that no pressure from the passage 28 can enter the chamber 16 to drive the piston forward, which therefore must depend for 80 making its advance-stroke on the pressure introduced therein through the port 19. Moreover, it is found in practice, that any pressure confined in the chamber 14 offers inappreciable resistance to the piston in making its forward stroke, because of leaking, under the force of the stroke, past the stem of the tool 13, which does 85 not fit tightly in the barrel-end.

With the stop 46 adjusted into the hole 49, the greater movement then permitted to the trigger before being arrested by the stop encountering the handle, will bring the valve to the intermediate position represented 90 in Fig. 10, wherein it uncovers more, as two-thirds of the area, of each duct 40 to supply more pressure through the ports 26¹, 26, to the chamber 14 and increase the extent of backstroke of the piston, which is still resisted by the pressure introduced into the chamber 16 through the ports 19¹, 19, this pressure being supplied from the valve-recess 45¹ with only one-third of the area of each port 41 then open to it. In other particulars the operation is the same as that described with the throttle-valve in the position represented 95 in Fig. 9.

The number of adjustments and form and arrangement of adjustable stop may be variously provided within my invention. Moreover, while I have selected for convenience in explaining my invention, the particular barrel and piston construction illustrated and the means for overcoming the dead-point of the piston shown and described in my said patent No. 837,856, it is not the intention to be understood as limiting its employment in those particular connections. The 100 feature of the aforesaid dead-point overcoming means essential for use as part of my present invention, whether employed, or not, for overcoming such dead-point, is a pressure-inlet port to the chamber 16 under controllable communication with the pressure-supply 105 by a throttle-valve; and the other essential feature of my invention is suitable means for regulating the extent of movement of the throttle for the piston-stroke-adjusting purpose herein described.

What I claim as new and desire to secure by Letters 120 Patent is—

1. In a pneumatic tool, the combination with the throttle-valve, of a trigger on the tool-handle engaging the valve for opening communication with the air-pressure supply, a plurality of holes in the trigger at varying distances from the handle, and a stop supported on the trigger and adjustable into engagement with any said hole to encounter the handle in depressing the trigger and arrest its valve-opening movement, for the purpose set forth.

2. In a pneumatic tool, the combination of a barrel con-

taining pressure-chambers, a handle on the barrel, a piston confined in the barrel to work between said chambers, the rear chamber having an inlet-port communicating with the supply of air-pressure for reciprocating the piston, a 5 throttle-valve controlling said communication, a trigger pivotally supported on the handle to engage said valve for opening communication with the air-pressure supply and provided with openings, and a spring-pressed rod rotatably supported on said trigger and longitudinally

movable on its support and provided with a hook on one 10 end adapted to register with and engage said openings and extend into position to encounter the handle in the inward movement of the trigger, for the purpose set forth.

HERMAN LEINEWEBER.
